US00D364610S

United States Patent [19]

Sanchez et al.

[11] Patent Number: Des. 364,610

[45] Date of Patent: **Nov. 28, 1995

[54] COMPUTER INPUT DEVICE

[75] Inventors: **Russell Sanchez; Steven T. Kaneko; Bridget Greenberg; Mike M. Paull**, all of Seattle, Wash.; **Robert Dillon**, Portland, Oreg.

[73] Assignee: **Microsoft Corporation**, Redmond, Wash.

[**] Term: **14 Years**

[21] Appl. No.: **23,196**

[22] Filed: **May 18, 1994**

[52] U.S. Cl. **D14/114**

[58] Field of Search ..... **D14/100, 114; 345/156-167; D13/158; D21/48; 178/18-19; 200/5 R, 5 A, 6 R, 6 A; 213/148 B; 273/148 B, 438; 74/471 XY**

CLAIM

The ornamental design for a computer input device, as shown and described.

DESCRIPTION

FIG. 1 is a front isometric view of a computer input device showing our new design;

FIG. 2 is a right side elevational view thereof, the left side elevational view being a mirror image;

FIG. 3 is a top plan view thereof;

FIG. 4 is a front elevational view thereof;

FIG. 5 is a bottom plan view thereof; and,

FIG. 6 is a rear elevational view thereof.
